CLAIM

I claim the ornamental design for a portion of a vehicle cowl hood, as shown and described.

DESCRIPTION

FIG. 1 is a perspective view of a portion of a vehicle cowl hood showing my new design;

FIG. 2 is a front elevational view of the portion of a vehicle cowl hood of FIG. 1;

FIG. 3 is a rear elevational view of the portion of a vehicle cowl hood of FIG. 1;

FIG. 4 is a right side elevational view of the portion of a vehicle cowl hood of FIG. 1;

FIG. 5 is a left side elevational view of the portion of a vehicle cowl hood of FIG. 1; and

FIG. 6 is a top plan view of the portion of a vehicle cowl hood of FIG. 1, the bottom being plain and unornamented. The broken line showing in the Figures is environmental only and forms no part of the claimed design.
